Primary Examiner — Marissa J Cash*Assistant Examiner* — Kayla Marie Bennett(74) *Attorney, Agent, or Firm* — ScienBiziP, P.C.(57) **CLAIM**

The ornamental design for a hammock stand bracket, as shown and described.

DESCRIPTION

FIG. 1 is a front, right and top perspective view of a hammock stand bracket, showing my design.

FIG. 2 is a rear, left and bottom perspective view thereof. FIG. 3 is another rear, right and top perspective view thereof of FIG. 1.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is an exploded view thereof.

The broken lines shown in the drawings are included for the purpose of illustrating portions of the hammock stand bracket that form no part of the claimed design.

1 Claim, 10 Drawing Sheets(56)
